UNITED STATES PATENT OFFICE.

ALVIN D. KEENE, OF MANSFIELD, OHIO, ASSIGNOR TO WESTINGHOUSE ELECTRIC & MANUFACTURING COMPANY, A CORPORATION OF PENNSYLVANIA.

HEARTH-TRAY VIBRATOR.

Application filed January 14, 1927. Serial No. 161,065.

My invention relates to furnaces and more particularly to furnaces having a tilttable hearth tray.

An object of my invention is to provide means for jarring or vibrating the hearth tray in its tilted position to facilitate the removal of material therefrom.

In practicing my invention, I provide, in conjunction with a tilttable hearth tray in an electric furnace and suitable tilting mechanism therefor, an electromagnetic device for vibrating the hearth tray, the energization of said electromagnetic device being controlled by the tray-tilting mechanism.

Fig. 1 is an elevation, in section, of an electric furnace embodying my invention; and

Fig. 2 is a development of the drum and cam groove shown in Fig. 1.

An electric furnace of the rotary hearth type, designated generally as 11, includes a frame 12 and layers 13 and 14 of suitable refractory material forming an annular furnace chamber 15. The hearths 16 are mounted for rotation upon a circular base 17 by means of standards 18 extending through an annular slot 19 in the bottom wall of the furnace. The base 17 carries a circular rack 20 and is revolved by suitable gearing 21 engaging said rack and driven by a motor 22. Heating elements 23 are mounted upon the top and bottom walls of the furnace chamber.

The mechanism for tilting said tray comprises preferably an electric motor 30 which, through suitable gearing 31, rotates a drum 32 in the face of which is cut a cam groove 33 as more clearly indicated in Fig. 2. A rod 34 extends through the top wall of the furnace and into the furnace chamber 15, the upper extremity of said rod engaging said cam groove 33 by means of a pin or roller 35. At the lower extremity of said rod, within the furnace chamber, is pivotally mounted a member 36, of substantially L-shape, one arm 37 of which is positioned to engage the hearth tray and the other arm 38 is positioned to bear against the side wall of the furnace chamber, so that movement about the pivot point is possible in only one direction.

On the exterior of the furnace is fixedly mounted a solenoid 40 within which is located a core 41. A rod 42, integral with or connected to the core 41, extends through the

side wall of the furnace and into the path of the movement of rod 34 and the member 36. A coil spring 43 is placed around the core extension 42 and between the core 41 and the furnace wall, so that normally the extension 42 is held out of the path of movement of rod 34 and member 36 in the position shown in Fig. 1. The energization of the solenoid winding is effected through an electric circuit including suitable source of alternating current electrical energy, such as conductors 44, and a switch 45. One contact 46 of the switch is fixed and the other 47 is carried by a lever 48 pivoted intermediate its ends for movement toward and away from the fixed contact. Carried upon the rod 34 is a lug or projection 49 for engagement with the switch lever 48 when rod 34 is in its raised position.

In operation the cylinder or drum 32 is rotated by means of motor 30, and as roller 35 of rod 34 rides along the cam groove, rod 34 is raised and member 36 engages the hearth tray 16 to tilt it. When the lifting movement is practically completed the portion 38 of the pivoted angle member 36 is in alinement with extension 42 on core 41, and at the same time lug 49 will engage switch lever 48 to cause contact members 46 and 47 to engage and to complete a circuit through the solenoid winding 40.

The energization of the solenoid winding attracts core 41 against the tension of spring 43 and forces extension 42 against arm 38 of the pivoted member 36 which causes vibration of the hearth tray 16. The heated material on tray 16 is thereby shaken or jolted off the tray and delivered to tank 50 through chute 51.

Various modifications of my invention are possible without departing from the spirit and scope thereof and I desire that only such limitations be placed thereon as are imposed by the prior art and set forth in the appended claims.

I claim as my invention:

1. In a furnace, the combination with a hearth tray movable in said furnace, and means for tilting said hearth tray, of electric means energized during a portion only of said tilting movement for vibrating said tray tilting means.

2. In a furnace, the combination with a hearth tray movable in said furnace, and motor driven tray tilting means, of electro-

100

110

magnetic means for causing vibration of said tray-tilting means.

3. In a furnace, the combination with a hearth tray movable in said furnace, and 5 motor driven tray tilting means, of electro-magnetic means for causing vibration of said tray-tilting means, and means operable by said tray-tilting mechanism to energize said electromagnetic means.

10 4. In a furnace, the combination with a hearth tray in said furnace and motor driven tray-tilting means, of electro-magnetic means for causing vibration of said tray-tilting means, and means controlled by said tray 15 tilting means for causing the energization of said electromagnetic means during a portion of the tilting movement of said tray.

5. In a furnace, the combination with a hearth tray movable in said furnace and 20 means for tilting said tray, of electromagnetic means for vibrating said tray, a normally open switch for controlling the energization of said electromagnetic means, and

means mounted upon said tray tilting means for closing said switch at a predetermined 25 point in the tray tilting movement.

6. In a furnace the combination with a movable hearth tray, and means for tilting said tray comprising a motor driven reciprocating member, a second member pivoted thereon and positioned to engage said tray, of means for causing vibration of said tray comprising a solenoid, a movable core therefor, a rod member secured to said core and extending into the path of movement of the 35 reciprocating member and pivoted member, means normally maintaining said core extension out of said path, and means operable by the tilting mechanism to energize said solenoid and force said rod member into engagement with said pivoted member to vibrate said hearth tray. 40

In testimony whereof, I have hereunto subscribed my name this 31st day of December, 1926.

ALVIN D. KEENE.
